COUPLER FOR USE IN FACSIMILE TRANSCEIVER

Donald L. McFarland and Glenn Reese, both of
2829 Maricopa St., Torrance, Calif. 90503

Continuation-in-part of design application Ser. No.
3,480, Aug. 16, 1966. This application Feb. 16,
1968, Ser. No. 10,596

Term of patent 14 years

Int. Cl. D14—03

U.S. Cl. D26—14

FIG.1

FIG.3

FIG. 4

FIG. 5

FIG. 2

FIG. 6

FIGURE 1 is an isometric view of the coupler;
FIGURE 2 is a front view of the coupler;
FIG. 3 is a rear elevation thereof;
FIG. 4 is a side elevation thereof;
FIG. 5 is a top plan view thereof; and
FIG. 6 is a perspective view of the coupler, the broken
lines have been shown for illustrative purposes only.

This is a continuation-in-part of design application Ser. No. 3,480, filed Aug. 16, 1966 and now Design Patent No. 211,354.

We claim:

The ornamental design for coupler for use in facsimile transceiver, as shown and described.
